Fig. 6

FIG. 1 is a perspective view of a fountain toothbrush illustrating my new design with a slide closure in the brush head illustrated in closed position and a removable cover in place;

FIG. 2 is a top plan view thereof with the slide closure in open position;

FIG. 3 is a side elevation thereof;

FIG. 4 is a bottom plan view thereof;

FIG. 5 is an end view thereof taken from the brush end;

FIG. 6 is an end view thereof taken from the rotatable cap end with a transparent knurled cap being used; and

FIG. 7 is an end view of a modified form of the brush shown in FIG. 1, wherein the only difference resides in an opaque end cap.

I claim:

The ornamental design for a fountain toothbrush, substantially as shown and described.
